UNITED STATES PATENT OFFICE.

AMOS L. KNIGHT, OF PHILADELPHIA, PENNSYLVANIA, ASSIGNOR TO LANSTON MONO-TYPE MACHINE COMPANY, OF PHILADELPHIA, PENNSYLVANIA, A CORPORATION OF VIRGINIA.

PRODUCTION OF ELEMENTS OF PRINTING-FORMS.

1,257,006.

Specification of Letters Patent. Patented Feb. 19, 1918.

Application filed February 3, 1917. Serial No. 146,492.

To all whom it may concern:

Be it known that I, AMOS L. KNIGHT, a citizen of the United States, and a resident of Philadelphia, county of Philadelphia, 5 State of Pennsylvania, have invented certain new and useful Improvements in the Production of Elements of Printing-Forms; and I do hereby declare the following to be a full, clear, and exact description of the 10 same, reference being had to the accompanying drawings, forming part of this specification, and to the characters of reference marked thereon.

My invention relates to the production of 15 typemetal elements of printing forms such as spacing material, leads, slugs and the like, and has for an object to produce such elements by casting them in successive, non-fused sections and ejecting said sections successively from the mold by causing the 20 ejecting movement of the last cast section to be transmitted to and accomplish the ejection of a previously cast section. Another and more specific object is to produce typemetal 25 elements by casting molten typemetal into a mold cavity one wall of which is formed by a face of a previously cast element, the heat of the metal being controlled in the mold in such a manner as substantially to 30 prevent fusion between the metal being cast and the metal of the previously cast element. When the metal of the last cast element has become cool it is given an ejecting 35 movement, pushing the previously cast element before it, until a position is reached in which its rearmost face will serve as a wall of the mold cavity for the next casting operation; and these operations may be repeated, if desired, to cause a regular casting 40 of new elements and ejection of previously cast elements, the latter being ready for use and requiring no cutting or sawing to length, planing, trimming or other finishing operations.

45 The invention will now be clearly set forth in connection with the following description of the accompanying drawings in which—

Figure 1 is a section of a mold and associated parts suitable for producing printers' 50 leads in accordance with the method of the present invention, the section being substantially in the vertical plane of the mold blade.

Fig. 2 is a cross section substantially on 55 the line 2—2 of Fig. 1.

Fig. 3 is a perspective view of the top or filler blade.

Fig. 4 is a perspective view of the filler 60 blade support, and

Fig. 5 is a perspective view of a modified form of filler blade and support.

Apparatus for producing continuous type metal strips by casting successive increments fused together is well known in the 65 printing art, a form of such apparatus being disclosed in my pending application Serial No. 864,894 filed October 3rd, 1914 (patent issued April 10, 1917, No. 1,222,415). With the aid of such apparatus 70 molten typemetal is forced into a mold cavity one wall of which is formed by a previously cast increment, the temperatures of the said wall and the molten metal being so controlled that the said wall is sufficiently 75 melted by the heat to cause the fusing together of the increment being cast and the one previously cast. This control of temperature at the meeting faces of two increments is preferably accomplished in practice 80 by locating the said fusible wall in proximity to the nozzle directing the molten stream into the mold cavity or by directing said stream angularly against said wall so that the incoming molten metal is washed 85 along the wall and conveys sufficient heat to it to melt it. After fusion of two increments, both are advanced by the mold blade sufficiently so that the rear face of the last cast increment is in position for 90 fusion to the succeeding cast and this process is repeated, the fused increments issuing from the mold being severed into the desired lengths by a suitable cutting apparatus. 95

The apparatus illustrated herein, is generally like that of the said application. The product of the present invention is, however, wholly different, being separate, non-fused elements instead of a continuous 100 fused strip, and the method of producing such product is also wholly different from that employed in the production of fused increment strip material.

It will be understood, of course, that the 105 mold shown (like that of the above mentioned application) is adapted to be associated with suitable mechanism for inject-

ing metal into the mold cavity, operating the mold blade, etc., all in properly timed relation. An example of such mechanism is the well known monotype casting machine, 5 represented in general by the patent to John Sellers Bancroft, No. 625,998, granted May 3th, 1899; but it will be apparent that the mold shown and the method described herein are susceptible of association with other 10 and simpler mechanism.

The mold shown in the accompanying drawing may be placed in the location for the mold shown and described in the last mentioned patent, and its blade may be 15 actuated through the medium of the cross blade actuating lever 246 of the patent. The pump nozzle 189 may be the same also as that of said patent and be connected with a metal pumping mechanism of the type of 20 that shown in the patent.

The mold may be the same in general construction as that shown and clearly described in my application Serial No. 864,894; and the mold illustrated herein partakes of 25 the general characteristics of that of the application so that it is not necessary here to describe it in minute detail. The base 3 of the mold is provided with a suitable nozzle-seat for the reception of the nozzle 30 189 and holds the type blocks 4 and 5 in a channel extending longitudinally of the mold blade 6, the bottom edge of which is slideable on the base block 3, the sides between the type blocks 4 and 5 and the top 35 against the filler blade 7 (see Fig. 3), held by the holder 8 (see Fig. 4), the latter resting upon the type blocks with the filler blade 7 extending between them and being held by a clamp 9 and abutment 10. The 40 mold blade 6 and the filler blade 7 are of a thickness corresponding with the point size of the element to be cast and the type blocks are separated at their rear ends by top and bottom liners of substantially the 45 same point size, the type blocks and liners being held by bolts 11. The type blocks are positioned laterally with the blade central over the nozzle by the packing plate 12 of suitable thickness and the type block 4 50 is secured rigidly to the base by the screws 41, (Fig. 1). To hold the type blocks on the base 3, tie bars 13 and 14, secured by bolts 15, are provided. The clamp 9 and abutment 10 are secured to the type block 55 4 by the collared bolt 16; and a shield 17 may be removably held upon the clamp 9 by the washer 18 yieldingly pressed against the shield by the spring 19 positioned between the washer and the head of the bolt 60 16. This shield is not always necessary but is provided to prevent accidental squirting of molten metal upwardly out of the mold when the filler blade 7 employed is not long enough to fill completely the space between 65 the type blocks up to the end of the mold.

As shown, however, the filler blade extends substantially to the ends of the type blocks. The tie bar 14 is grooved at 20 to permit of the easy assembling of the filler blade without removing said tie bar.

The type block 5 is provided with a triangular vent opening which gradually enlarges toward the discharge end of the mold; and this is conveniently accomplished, as shown, by constructing the block 5 in two parts, the lower part being grooved in the form of the vent opening and the upper part 51 being secured to the lower part with the bottom wall covering the groove. In the vent opening a pusher 21, triangular in section to fit said opening, is adapted to slide, said pusher being loosely secured to the blade by a lug thereon which seats in the rectangular hole 22 in the blade. The lug nicely fits the hole longitudinally of the blade but is smaller than the hole in a vertical direction, so that an absolutely accurate vertical positioning of the hole with respect to the vent opening is unnecessary. It will be understood of course that the blade is slidably fitted in the mold so that it may be advanced and retracted and that the pusher is slideable in the vent opening and is moved back and forth by the blade in unison therewith. The blade is moved by an operating bar 23 provided at one end with a stud 24 extending into an aperture in the blade, its opposite end being connected by a spring box connection with the actuating lever 246 previously mentioned.

Fixed to a stationary part of the machine stops 25 and 26 are provided for coacting with the shoulder 27 on the bar 23 and with the rear end of the mold blade respectively, the stop 25 governing the advance movement of the blade and the stop 26 the rearward movement thereof. Pica pieces 27¹ or the like may be hung on the hooks 28 secured to the stops so as to adjust in a manner well understood the blade stroke. The blade is represented in Fig. 1 in its advanced position by full lines and in retracted position by dotted lines. To support its rear end when retracted a supporting block 29 secured by screws 30 to the bottom of the type block 5 is provided. Also a channeled guide member 31 for guiding the top, bottom and one side of the blade is secured to the top of the type block 5 by the extension 32 and screws 33, said member being provided with a slot 34 to prevent interference with the pusher 21 when the latter is in its retracted position.

A pressure screw 35 threaded in the sleeve 36 passing through the front wall of the base 3 and non-rotatably secured thereto by reason of its square head 37, is adapted to be rotated by the lever 39 operated from a suitable part of the machine in timed rela-

tion to the casting and blade moving operations so as to place pressure upon and remove it from the block 5, near the discharge end thereof. In this way the typemetal 5 element is periodically clamped and released for advancement between the type blocks. As the elements are discharged from between the type blocks they pass between the fixed diagonal blade 40 of the brake or friction device thereof, and the plate 41 spring 10 pressed toward said blade. This device acts frictionally to hold the elements and to cut off the typemetal which has escaped through the air vent and has been advanced in unison with the element by the pusher 21.

Instead of the filler blade 7 and its holder 8 a combined blade and holder 42 such as is shown in Fig. 5 may be used.

In operation each element after being cast 20 is advanced by the blade, the latter being moved by the lever 246 and the rod 23 connecting said lever and the blade, until the shoulder 27 on the rod 23 abuts the stop 25, any further motion of the lever 246 being 25 taken up by the spring box in the said connection. The blade will now be in the position shown in full lines in Fig. 1. The blade is then retracted to the dotted position in which its rearward end abuts against the stop 26, any further motion of the lever 246 being here also taken up by the spring box. When the blade is in retracted position the lever 39 is caused to rotate the pressure screw 35 so as to spring the type block 5 30 slightly and firmly clamp the element just advanced, after which the pump mechanism forces molten typemetal into the mold cavity formed by the forward wall of the blade 6 in retracted position, the rearward wall of 35 the element previously cast, the side type blocks the base 3, and the filler blade 7. It will be observed that the forward end of the mold blade is a vertical plane surface so that the typemetal element produced may have 40 straight parallel ends. After a short period of time necessary for the cooling and hardening of the metal, which is preferably hastened in the usual manner by circulating cooling fluid through channels in the mold, 45 the above operations are repeated. This method of operation differs from that set forth in the previously mentioned application in that in the present case the heat of the molten metal when it reaches the mold 50 cavity wall formed by the previously cast element, is not sufficient to melt the said wall or a part of it sufficient to cause substantial fusion of the two elements. This heat control is accomplished by maintaining 55 the said wall at a temperature sufficiently low to prevent fusion. In practice a flow of molten metal within the mold is usually brought about prior to its meeting with the said wall, the metal being cooled during said 60 flow so that although it is mobile enough to

fill all the corners of the cavity and reaches the typemetal wall of the cavity while in mobile condition, it is insufficient as to its heat content at the moment of reaching said wall to heat up the latter to a fusion temperature. 70 The wall is preferably water cooled and of course it is metallic and possesses good heat conductivity; moreover it is clamped tightly on the mold and these circumstances aid in keeping it at a non-fusing temperature. In 75 some cases the whole charge of molten metal may contain insufficient heat to produce a fusion temperature of the wall.

I claim—

1. The improvement in the art of producing elements of printing forms which comprises casting said elements in a mold in successive, non-fused sections and ejecting said sections successively from the mold by causing an ejecting motion of the section 80 last cast to accomplish the ejection of a previously cast section.

2. The improvement in the art of producing elements of printing forms which comprises casting said elements in a mold in 90 successive, non-fused sections, each section immediately preceding the last cast section being maintained immovable during the casting of said last cast section, then releasing said preceding section and causing an ejecting motion of the last cast section to accomplish the ejection of a previously cast section. 95

3. The improvement in the art of producing elements of printing forms which comprises injecting the molten charge for each section into a mold cavity the discharge end of which is closed by clamping the previously cast element between the side walls of the mold, then releasing said previously cast 100 element and causing an ejecting movement of the element last cast to accomplish the ejection from the mold of a previously cast section. 105

4. The method of forming type metal elements of printing forms which consists in casting the elements in successive sections in contact with each other and in maintaining each solidified section at a temperature sufficiently low to prevent fusion of its surface 110 by contact with the molten metal of the succeeding section.

5. The method of forming type metal elements of printing forms which consists in casting the elements in successive sections in 120 contact with each other and in maintaining each solidified section at a temperature sufficiently low to prevent fusion of its surface by contact with the molten metal of the succeeding section, and in feeding the elements forward in unison as they successively congeal to leave space for the formation of a succeeding section. 125

6. The method of forming type metal elements of printing forms which consists in 130

casting the elements in successive sections in contact with each other at one edge and in maintaining each solidified section at a temperature sufficiently low to prevent fusion of its surface by contact with the molten metal of the succeeding section.

7. The method of forming type metal elements of printing forms which consists in casting the elements in successive sections 10 in contact with each other at one edge and in maintaining each solidified section at a temperature sufficiently low to prevent fusion of its surface by contact with the molten metal of the succeeding section, and 15 in feeding the elements forward in unison as they successively congeal to leave space for the formation of a succeeding section.

8. The method of forming a typemetal element of a printing form which comprises 20 forcing molten typemetal into a mold cavity one end wall of which is formed by previously cast typemetal and causing the molten typemetal within the mold to flow by an indirect path into contact with said wall, 25 whereby substantially no fusion of the molten typemetal with said wall takes place.

9. The method of forming a typemetal element of a printing form which comprises forcing molten typemetal into a mold cavity 30 one wall of which is formed by previously cast typemetal and causing such molten metal to traverse the mold cavity before reaching said wall, whereby substantially no fusion of the molten typemetal 35 with the wall takes place.

10. The method of forming a typemetal element of a printing form which comprises directing molten typemetal into a mold cavity and toward the central portion thereof, 40 one wall of said cavity being formed by previously cast typemetal whereby substantially no fusion of the molten typemetal with said wall takes place.

11. The method of forming a typemetal element of a printing form which comprises 45 forcing a charge of molten typemetal into a mold cavity one wall of which is formed by previously cast typemetal, and causing said charge to flow within the mold in contact with cooling surfaces thereof before it 50 comes into contact with said typemetal wall,

whereby substantially no fusion of the molten typemetal with the wall takes place.

12. The method of forming a typemetal element of a printing form which comprises forcing molten typemetal into a mold cavity one end wall of which is a plane surface formed by the end of a previously cast typemetal element and the other end wall of which is a plane surface constituted by the end of the mold blade, and the side walls of which are formed by fluid-cooled type blocks, and causing the molten typemetal to flow first between said type blocks and thereafter toward and into contact with said typemetal wall, whereby when the molten typemetal reaches said typemetal wall substantially no fusion therewith takes place.

13. The method of forming a typemetal element of a printing form which comprises introducing molten typemetal into a mold cavity one end wall of which is a plane surface formed by the end of a previously cast typemetal element and the other end 7 wall of which is a plane surface parallel to the first named plane surface and constituted by the end of the mold blade, and the side walls of which are formed by fluid-cooled type blocks, said molten typemetal 8 being introduced into the mold cavity substantially centrally thereof and in the form of a stream substantially parallel to said end walls.

14. The method of forming typemetal elements of printing forms which comprises forcing molten typemetal into a mold cavity one wall of which is formed by previously cast typemetal, and causing the molten metal within the mold to flow into contact with 9 said wall by an indirect path whereby substantially no fusion of the molten typemetal with said wall takes place, causing said molten typemetal to cool to form an element of a printing form and then advancing said 9¹ element until the rearward face is in the position occupied by said typemetal wall during the casting of said element whereby the said rearward face of said element forms one wall of the mold cavity for a subsequent 10 cast, and repeating the above operations.

AMOS L. KNIGHT.
